UNITED STATES PATENT OFFICE.

ISAAC N. HOLLINGSWORTH, OF LAUDERDALE, MISSISSIPPI.

FOUNTAIN-BRUSH.

1,097,630.

Specification of Letters Patent.

Patented May 26, 1914.

Application filed November 7, 1913. Serial No. 799,790.

To all whom it may concern:

Be it known that I, ISAAC N. HOLLINGSWORTH, a citizen of the United States, residing at Lauderdale, in the county of Lauderdale and State of Mississippi, have invented a new and useful Fountain-Brush, of which the following is a specification.

This invention relates to improvements in fountain brushes.

10 An object of the present invention is to provide a fountain brush to which a water supply tube may be easily attached for the supplying of a liquid to the brush bristles.

15 A further object of the present invention is to provide a fountain brush which may be used in connection with a portable bath apparatus which will be simple in design, cheap to manufacture and the simplicity of the design and rigidity and strength of the 20 structure rendering the fountain brush a desirable and useful article.

With the foregoing and other objects in view, which will appear as the description proceeds, the invention resides in the combination and arrangement of parts and in the details of construction hereinafter described and claimed, it being understood that changes in the precise embodiment of the invention herein disclosed can be made within 25 the scope of what is claimed without departing from the spirit of the invention.

In the drawings accompanying this specification, and forming a part thereof, the preferable form of my invention has been 30 shown in which:

Figure 1 is a side sectional view of my improved fountain brush and illustrating the internal construction thereof. Fig. 2 is a top plan view with a portion thereof removed. Fig. 3 is a fragmental sectional view of the liquid supply nozzle which is positioned within the brush bristles and adapted to supply a liquid thereto.

Referring to the drawings in which similar reference numerals designate corresponding parts throughout the several views, 4 is the back of the brush and to which the brush bristles 5 are rigidly secured. The said back is provided with a bore 6 extending in from 45 the rear edge and which bends downwardly as at 7 terminating approximately central of the brush bristles, and which bore provides a passage through which a pipe 8 is forced and which when it has attained a position as illustrated in Fig. 1 is adapted to

supply a liquid to the center of the brush bristles.

The pipe 8 extends through the bore 6 and is provided with a threaded end 9 which extends down within the brush bristles as illustrated in Fig. 1. The opposite end of the pipe 8 extends for a considerable distance beyond the rear wall of the brush and is provided with a threaded end 10. The threaded end 10 provides means for securing 65 a nipple to the pipe.

In order to provide for the proper manipulation of the brush, the handle is secured to the pipe 8 and is formed in two sections. The section adjacent the brush comprises the body portion 11 provided with a longitudinal bore 12 extending therethrough and which receives the pipe 6 therein. A metallic washer 13 is provided between the meeting ends of the handle 11 and the rear wall of the brush back. Rigidly secured to the opposite end of the handle body portion 11 is the sleeve 14 including a reduced externally threaded portion 15 the extreme end of which terminates short of the 80 end of the pipe 8 so as to leave the threaded end 10 thereof exposed. A hose pipe engaging nipple 16 is internally threaded as at 17 and is adapted to engage the pipe 8 and act as a nut forcing the sleeve 14 into contact 85 with the handle 11 and rigidly securing the same in place, thus locking the various parts upon the pipe 8 and rigidly securing the same thereto.

As will be apparent from a reference to Fig. 2 the nut like nipple 16 is provided with a flanged or corrugated outer surface so as to rigidly secure a hose pipe 17 thereto and which is connected to some suitable liquid supply to be delivered to the brush 95 bristles. An auxiliary handle 18 is provided with a bore 19 extending longitudinally therethrough through which the hose pipe 17 extends and is provided with a threaded end 20 adapted to engage the reduced portion 15 of the sleeve. Thus the auxiliary handle 18 will be rigidly secured to the handle 11 which latter in its turn is by reason of the nut like nipple 16 and pipe 8 rigidly secured to the brush back 4. The auxiliary handle in addition to elongating the handle 11 provides a guide entrance for the hose pipe and also conceals the joint between the same and the pipe 8 and furthermore as illustrated in Fig. 2 the portion 21 of the 110

auxiliary handle 17 is of a diameter just sufficient to fit nicely over the pipe 17 and prevent the same from becoming accidentally detached from the nipple 16. In this connection it is to be noted that the handle 18 has been spoken of as being provided with a threaded end but as illustrated in Fig. 1 the handle is provided with a metallic sleeve 18' which is provided with the threads as it 10 will be readily appreciated the handle 18 will be formed of wood or some equivalent and light material which it would not be practical to thread.

The cap 22 is internally threaded and 15 adapted to engage the threaded end 9 of the pipe 8. The cap 22 is provided with a plurality of apertures 23 extending radially through the side walls thereof and adapted to direct the flow of liquid to the various 20 brush bristles. In my improved fountain brush there will be little or no danger of the hose which supplied the liquid to the brush becoming detached and furthermore the juncture between the hose and the brush 25 is adequately protected. The handles are preferably corrugated as shown so that a sufficient grip may be had thereupon for the ready manipulation of the brush. The entire construction is of a simple nature forming 30 a most desirable article.

Having thus fully described the invention what is claimed is:—

1. A fountain brush comprising a brush back provided with an aperture extending 35 therethrough and communicating with the bristle receiving portion thereof, a tube positioned within said aperture, a handle provided with a bore extending longitudinally therethrough mounted upon said tube, a 40 sleeve fitting over the said tube contacting with the handle and provided with a threaded portion, a hose pipe nipple threadedly engaging the extremity of said tube and contacting with the said sleeve and adapted to 45 force the same and said handle into forced

contact with the brush back to hold the same rigidly so positioned, and an auxiliary handle threadedly engaging the threaded portion of said sleeve extending over the hose pipe nipple and adapted to house the hose 50 pipe juncture with the said hose pipe nipple.

2. In a fountain brush the combination of a brush back provided with an aperture extending in from the rear wall thereof and extending at right angles and terminating 55 at the center of the bristle receiving portion, a crooked tube permanently positioned in said aperture and with the threaded ends thereof extending therebeyond, a liquid distributing cap provided with a plurality of 60 radial apertures engaging one end of said tube and adapted to distribute the liquid as it flows therefrom to the brush bristles, a handle provided with an aperture extending therethrough slidably mounted on the opposite end of said tube, a sleeve with a reduced portion engaging the said handle and mounted slidably upon said tube, a hose pipe nipple internally threaded and engaging the threaded end of said tube contacting 70 with the reduced portion of said sleeve and adapted to force the same into forced contact with the handle and the latter into forced contact with the brush back, and also a handle with a bore extending therethrough, a 75 hose pipe extending through said bore and fitting over said hose pipe nozzle, said auxiliary handle contacting with the outer extremities of said hose pipe next between the same and the hose pipe nipple, and a sleeve 80 rigidly secured to the auxiliary handle and engaging the reduced portion of the aforementioned sleeve.

In testimony that I claim the foregoing as my own, I have hereto affixed my signature in the presence of two witnesses.

ISAAC N. HOLLINGSWORTH.
